C. Storwells

UNITED STATES PATENT OFFICE.

HERBERT H. DREW, OF WATERTOWN, WISCONSIN, ASSIGNOR TO WATERTOWN TABLE SLIDE CO., OF WATERTOWN, WISCONSIN.

EXTENSION-TABLE SLIDE.

Application filed June 6, 1927. Serial No. 196,856.

This invention pertains to improvements in extension table slides, and more particularly to a mechanism for equalizing the movement of the slides.

5 Primarily the invention has for its object to provide an improved structure of the foregoing character which is simple, inexpensive, efficient and durable, and which insures proper alignment and operative engagement 10 between the movable parts under any and all conditions.

More specifically the invention pertains to an improvement in what is termed the rack and pinion type of equalizer, wherein considerable difficulty and objections have been 15 encountered in providing and maintaining the proper alignment between the racks carried by the movable slides and pinions secured to the stationary slides. The present 20 invention provides a self-adjusting pinion which will readily accommodate itself to any variation between the racks, thus rendering the same self-centering and resulting in the reduction of bind, wear, friction, noise of operation, and cost of manufacture. In addition 25 to the foregoing advantages, numerous others will become apparent as the description proceeds.

With the above and other objects in view, 30 which will appear as the description proceeds, the invention resides in the novel construction, combination and arrangement of parts substantially as hereinafter described and more particularly defined by the appended claims, it being understood that such 35 changes in the precise embodiment of the herein disclosed invention may be made as come within the scope of the claims.

In accompanying drawings is illustrated 40 one complete example of the physical embodiment of the present invention constructed according to the best mode so far devised for the practical application of the principles thereof.

45 Figure 1 is a fragmentary plan view of a conventional table slide set with the invention attached thereto.

Figure 2 is a longitudinal section taken on the line 2—2 of Figure 1, and

50 Figure 3 is a transverse section taken on the line 3—3 of Figure 1.

Referring now more particularly to the

accompanying drawings, wherein the invention is shown attached to a set of extension table slides of conventional structure, the 55 numeral 1 designates a fixed center rail adapted to be secured to a pedestal, or other form of suitable support, in the usual manner.

Positioned upon opposite sides of the 60 fixed rail 1 is a pair of slidable rails 2 which are secured to the respective end table sections in a manner well known to those skilled in the art.

Both the fixed rail 1 and the sliding rails 65 2 are provided with dove-tailed grooves 3 in their abutting faces, which grooves receive the guide members 4 that serve as slidable connections between the fixed and movable rails.

As pointed out in the objects, the present 70 invention consists primarily in an improvement in the equalizing means employed, and therefore it will be understood that the specific structure of the slides form no part 75 of the present invention other than in the combinations defined by the claims.

The equalizing means employed for equalizing the movement of the sliding rails 2 is of the rack and pinion type, and embodies a 80 pair of racks 5 secured horizontally to faces of the sliding rails 2 with their teeth projecting towards the fixed rail 1. A bracket comprising a strap 7 is provided with offset ends 8 and 9 respectively, the end 8 being pivotally secured to the face of the fixed rail 1 by means of the screw 10. The opposite end 9 of the bracket 7 is provided with an elongated slot 11 for the reception of the screw 12, which cooperates with the screw 10 to secure the bracket 7 to the fixed rail 1, and at the same time permit oscillatory movement of the bracket. Carried by the bracket 7 intermediate its offset ends and positioned between the bracket and the face of the fixed 95 rail 1, is the pinion 13 which extends over the slide rails 2 and engages the opposed racks 5.

As previously explained, the generic principle of the rack and gear type of equalizer is 100 well known in the art, but considerable difficulty has been encountered in maintaining proper alignment and operative engagement between the racks and pinion employed, due

to the fact that the conventional slides are manufactured from wood, which is subject to more or less warping with changes of climatic conditions; and, further, due to wear in the connections between the slides, the same are inclined to become loose with continued use which results in disalignment between the racks and pinion.

It has also been found that very close and precise machine work is required in order to obtain a proper engagement between the racks and pinions which would permit of essential easy and quiet operation. Obviously any disalignment between the racks and pinion would result in considerable friction and wear, requiring additional effort to operate the slides.

From the description of the present structure taken in connection with the drawing, it will be obvious that applicant's method of mounting the pinion on the fixed rail provides a floating pinion, which will readily center itself for proper engagement with the opposed racks, thus eliminating friction, noise of operation, and compensating for any warp or twist in the rail sections.

A further advantage of this arrangement resides in the fact that strain on the pinion is perfectly equalized, which reduces wear upon the parts and increases their life. Also, because of the compensating feature of the present structure, precise machine work is unnecessary, and slight defects in workmanship will not seriously affect the ease of operation.

Further, the present invention materially improves the appearance of the equalizing mechanism in that the bracket covers the greater portion of the pinion, which also protects the same against disalignment or damage during shipping.

While one specific method of movably securing the pinion to the fixed rail has been illustrated and described in considerable detail, it is obvious that various means may be employed for accomplishing the same result. Therefore, the present invention is only to be limited to the scope of the appending claims.

I claim:

1. An extension table slide comprising a fixed rail, a pair of movable side rails connected with and slidably guided on opposite sides of the fixed rail, opposed longitudinal racks secured horizontally to the movable rails, and a laterally floating pinion secured to the fixed rail and engaging the racks carried by said movable rails and means for guiding said pinion laterally with respect to said racks. 50

2. An extension table comprising a fixed rail, a pair of movable side rails connected with and slidably guided on opposite sides of the fixed rail, opposed longitudinal racks secured horizontally to the movable rails, a bracket pivotally secured to said fixed rail, and a pinion carried by said bracket for engagement with the racks carried by said movable rails. 60

3. An extension table comprising a fixed 70 rail, a pair of movable side rails connected with and slidably guided on opposite sides of the fixed rail, opposed longitudinal racks secured horizontally to the movable rails, a bracket having one end secured to the fixed 75 rail and its opposite end movably attached to said fixed rail, and a pinion carried by said bracket intermediate its ends for engaging the racks carried by said movable rails.

4. An extension table comprising a fixed rail, a pair of movable side rails connected with and slidably guided on opposite sides of the fixed rail, opposed longitudinal racks secured horizontally to the movable rails, a 85 bracket having offset ends, means for pivotally attaching one of said ends to said fixed rail, means for movably securing the opposite end to said fixed rail, and a pinion carried by said bracket intermediate the bracket 90 and the fixed rail for engagement with the racks carried by said movable rails.

In testimony that I claim the foregoing I have hereunto set my hand at Watertown, in the county of Jefferson and State of 95 Wisconsin.

HERBERT H. DREW.
